UNITED STATES PATENT OFFICE

143,395

DESIGN FOR A POWER TAKE-OFF UNIT

Walter F. Benning, Toledo, Ohio, assignor to
Willys-Overland Motors, Inc., Toledo, Ohio, a
corporation of Delaware

Application November 18, 1944, Serial No. 116,443

Term of patent 14 years

(Cl. D55—1)

To all whom it may concern:

Be it known that I, Walter F. Benning, a citizen of the United States, residing at 3343 Aldringham Road, Toledo, county of Lucas, and State of Ohio, have invented a new, original, and ornamental Design for a Power Take-Off Unit, of which the following is a specification, reference being had to the accompanying drawing, forming part thereof.

In the drawing, Figure 1 is a perspective view of the power take-off unit showing my new design;

Figure 2 is a top plan view of the power take-off unit shown in Figure 1;

Figure 3 is a rear elevational view of the power take-off unit; and

Figure 4 is an end view of the power take-off unit.

The dominant features of my design of power take-off unit reside in the portions shown in full lines on the drawing.

I claim:

The ornamental design for a power take-off unit, substantially as shown and described.

WALTER F. BENNING.
